UNITED STATES PATENT OFFICE.

TALBOT G. MARTIN, OF CHICAGO, ILLINOIS, ASSIGNOR, BY MESNE ASSIGNMENTS, TO AUTOMATIC ELECTRIC COMPANY, A CORPORATION OF ILLINOIS.

AUTOMATIC TELEPHONE AND SELECTIVE SIGNALING SYSTEM.

Application filed November 30, 1907. Serial No. 404,512.

To all whom it may concern:

Be it known that I, TALBOT G. MARTIN, a citizen of the United States of America, and resident of Chicago, Cook County, Illinois, 5 have invented a certain new and useful Improvement in Automatic Telephone and Selective Signaling Systems, of which the following is a specification.

My invention relates to telephone systems 10 in general, but more particularly to automatic or semi-automatic telephone exchange systems, and especially to systems in which selective ringing on party-lines is necessary or desirable.

15 The principal object of my invention is to provide an improved arrangement by which the required ringing current for the ringer of any particular substation on the party-line may be readily selected and applied to the called line.

Special objects are to provide an automatic step-by-step switch for selecting and connecting the different sources of ringing current to the lines of the called subscribers, 25 the said automatic switch being operative to connect any one of the different sources of ringing current with the party-line, whereby the ringers thereon are selectively operated in any desired or well-known manner, as, for example, by currents of different 30 frequencies; to provide a party-line automatic telephone system in which the calling of all except the last digit of the called number will extend the connection from the 35 called line to the party-line, and in which the operation of the calling subscriber's dial or other call-transmitting mechanism for the last or final digit will then result in the selection of a certain one of a number 40 of generators or other sources of ringing current, depending upon which party-line subscriber is called, and in the connection to the party-line of the particular generator or source of ringing current thus arbitrarily selected by the calling subscriber; 45 and to provide certain details and combinations and features of improvement tending to increase the general efficiency of a party-line telephone system of this particular character.

To the foregoing and other useful ends, my invention consists in matters hereinafter set forth and claimed.

In the accompanying drawings Figure 1

represents diagrammatically a party-line 55 equipped with a number of telephones A, A¹ and A². Below the subscribers' substations there is represented central office equipment employed in establishing a connection. A first-selector switch C is allotted to the line occupied by the substations A, A¹ and A². At D there is represented diagrammatically a second-selector switch and at E a connector switch of an improved type. At B there is shown a central battery having its positive terminal 60 preferably grounded at G.

Fig. 2 shows diagrammatically a second party-line equipped with the substations A³, A⁴ and A⁵. To this line there is allotted at the central office the first-selector switch F which is the same as the selector switch C.

The substations may be of any suitable or approved type. Those in connection 75 with which I have elected to illustrate my invention are all alike. Substation A, for example, comprises a receiver 2, a switch-hook 3 for controlling the substation circuits, which controlling operations are accomplished through the medium of any suitable means, such as the cam-arms 4, 5 and 6. As the switch-hook is lowered the cam-arm 4 momentarily presses the release springs 7, 8 and 9 into engagement, whereby the substation line conductors may be grounded simultaneously. When the switch-hook is down the cam-arm 5 engages the spring 10, thereby bridging the ringer 11 in series with the condenser 12 across the line. 80 Furthermore, when the switch-hook is down and said cam-arm 5 disengages the springs 13, 14 and 15, thus breaking the local battery circuit which includes in series the primary winding 15^a, transmitter 16 and 85 local battery 17. When the springs 13 and 14 disengage the lock-out relay 17^a is disconnected from the rotary line conductor. The substation ground circuit is normally 90 broken between the ground springs 18 and 19 by the cam-arm 6; but when said springs are together, and the relay 17^a is in normal condition, ground is provided to the ground post 20 and to the release spring 7, as is 95 usually the case in telephones of this type. 100 The said substation comprises the usual induction-coil 21 having the primary winding 15^a and secondary winding 22. Being an 105

automatic substation it is provided with the usual vertical and rotary impulse springs 23 and 24. Said substation is, of course, provided with a dial (not shown) which is 5 secured to the shaft 25, together with the locking dog 26. Furthermore, there is a locking cam 27 that locks the dog 26 while the receiver is on the switch-hook, to prevent a rotation of the dial. For operating 10 the impulse springs 23 and 24 the substation is provided with an impulse wheel 28 that is secured to the shaft, which impulse wheel carries on its periphery the so-called vertical impulse teeth 29 and one rotary im- 15 pulse tooth 30. The said impulse teeth are so arranged that when the dial is drawn down the impulse springs are not carried into contact with the ground post 20; but as the dial returns, first the vertical teeth 20 engage the vertical impulse spring 23, and after they have completed their work the rotary impulse tooth 30 operates the rotary impulse spring 24. In this operation the subscriber's vertical line conductor 31 25 is first given a number of ground impulses, and then the rotary line conductor 32 is given one ground impulse. It will be seen that as long as the dial is out of normal position the dog 26 permits the primary circuit 30 springs 33 and 34 to separate, thus preventing the impulses that are delivered to either line conductor from passing to the other. The means whereby the subscriber may signal the called subscriber comprises 35 the push-button spring 35 which normally engages the contact point 36; but when the button 37 is pressed the spring 35 engages the contact point 38, whereby the vertical line conductor 31 may be grounded. The 40 substation is also provided with a governor (not shown) for controlling the speed of the impulse wheel 28 and the switch-hook 3. Furthermore, the lock-out relay 17^a is provided with the armature 39, so that when 45 the relay is energized and the switch-hook 3 is up, the armature 39 is attracted, disengaging the springs 40 and 41, and the armature is locked in its attracted position by the locking spring 42, as shown at sub- 50 station A'; but when the switch-hook is lowered the rod 43, which is attached to the switch-hook 3, slides downward in front of the armature 39, carrying the locking spring 42 out of engagement with the armature 39.

The first-selector switch shown at C is of the general type described in United States Patent No. 815,321, granted March 13, 1906, to Keith, Erickson and Erickson, having 60 some slight modifications—that is, the rotary side of the line is retained normally open by the switch shaft, instead of being normally closed as is usually the case. Among other details, the first-selector switch C embodies 65 the following well-known devices and cir-

cuits: The switch shaft (not shown) carries the vertical and rotary wipers 45 and 46, respectively, and the private wiper 47. The side switch is well known and comprises the side switch wipers 48, 49, 50 and 70 51, which may be designated as the vertical, rotary and private side switch wipers, and the rotary magnet wiper, respectively. The side switch is under the control of the private magnet 52, and in the normal or first 75 position of the side switch the wipers 48, 49, 50 and 51 occupy the contact points 53, 54, 55 and 56, respectively; in the second position they rest on the contact points 57, 58, 59 and 60, respectively; and in the third 80 position the contact points 61, 62, 63 and 64 are engaged by their respective wipers. Through the medium of the vertical line relay 65, and while the side switch is in first 85 position, the subscriber controls the vertical magnet 66, which latter operates to raise the switch shaft and wipers 45, 46 and 47 vertically. By means of the rotary line relay 67, and while the side switch is in the first position, the subscriber controls the private magnet 52 and, therefore, the side switch. While the side switch is in second 90 position the rotary magnet 68, which operates to carry the switch shaft and wipers 45, 46 and 47 in a rotary direction, is energized. 95 The vertical and rotary line relays 65 and 67, acting conjointly, provide means whereby the subscriber controls the release magnet 68^a while the side switch is in the first or second position. If the side switch passes 100 to third position, then, since the selector is of the trunk-release type, the selector is controlled through the next switch (with which latter a connection is then established) and through the private wiper 47 and by means 105 of the back-release relay 69. The bridge-cut-off relay 70 is provided to open the connection between the line relays 65 and 67 and between said relays and battery B. This is desirable because if the relays are not disconnected from each other and battery the ringing current for signaling the subscriber may operate either or both of the relays 65 and 67, and thus cause some interference with the switch. It is also desirable to remove the 110 bridge formed through the said relays from across the line to give the voice-currents as clear a path as possible. In addition, the selector switch is provided with a private normal relay 71 by means of which the 115 guarding potential at the connector bank is momentarily removed to enable a subscriber to call back on his own line. The switch shaft also carries the normal arm 72 which, when the shaft is in normal position, retains 120 the spring 73 out of engagement with the spring 74, thus disconnecting the rotary line conductor 32 from the side switch wiper 49; but when the shaft is given its first vertical 125 step the springs 74 and 73 come together. 130

The second-selector D is of the same general type as the selector switch C, with the exception that there are no normal conductors such as the normal conductors 75 and 76 of the selector switch C. There is also no necessity in the second-selector for a bridge-cut-off relay such as the relay 70 of the selector C, and it is also omitted; and the line relays are connected directly to battery lead. The private normal conductor, such as the private normal conductor 77 of the selector C, is not necessary in connection with the second-selector and is also omitted. Since like parts are likewise represented throughout the drawings, the vertical magnet 78 and the rotary magnet 79, the release magnet 80, and the private magnet 81 will be recognized and understood. The said private magnet 81, of course, controls the side switch wipers 81^a, 82, 83 and 84, the said private magnet also controlling the circuit of the vertical magnet 78 in the usual manner by means of the springs 85 and 86, but not the circuit of the release magnet, for the release magnet spring is omitted. The vertical movement of the switch shaft and, therefore, of the wipers 87, 88 and 89 is controlled by the vertical magnet 78 and the rotary movement by the rotary magnet 79, the said rotary magnet circuit being provided with the usual interrupter springs 90. The operative magnets of the switch are, of course, controlled by the subscriber through the medium of the vertical and rotary line relays 91 and 92, as is well known. Said relays have under their control the usual springs 93, 94 and 95 and, in addition, the trunk-release springs 96 and 97, whereby the said switch may be released when the side switch wipers are in first or second position. After the side switch passes to third position and connection is established with the next switch the release is controlled by the back-release relay 98.

The connector switch E is an improvement upon the general type of connector switch disclosed in United States Patent No. 815,176, granted March 13, 1906, to Keith, Erickson and Erickson. In addition to the usual connector features my improved switch E possesses a frequency selecting arrangement which admirably adapts it to party-line work in which the signaling is selective. As shown in Fig. 1, the central office may be provided with several ringer generators R¹, R², R³, R⁴, etc., each designed to deliver current of a different character or frequency. Also, the ringers at the different substations are arranged to respond to generator currents of certain frequencies. For example, the ringer of substation A⁵ responds to the signaling current of generator R¹, substation A⁴ is signaled from generator R², and substation A³ is signaled only when the terminals of the generator R³ are bridged across the line. Hence, when it is desired to signal a particular substation on a party-line the particular ringer generator R, which is effective in sounding the ringer of the desired station, is selected from the group and its terminals bridged across the called line. This frequency selecting arrangement which I have combined with the connector E comprises the rotary magnet 99 and ratchet release magnet 100. The rotary magnet 99, when energized, attracts its armature 101, whereby the pawl 102 engages the ratchet wheel 103, advancing the latter one step. As the ratchet wheel advances, the ratchet pawl 104 retains the wheel in its advanced position. Mounted upon the shaft of the ratchet wheel 103 are the wipers 105 and 106 which are adapted to slide over a bank of contacts to which are connected the ringer generators R¹, R², R³ and R⁴. The ratchet release magnet 100, upon energizing, attracts the ratchet pawl 104, withdrawing the latter from engagement with the ratchet wheel 103. The ratchet wheel then returns to normal position, with the wipers 105 and 106 to the left of the bank contacts 107, thereby restoring the generator selective arrangement to normal position. The connector switch shaft (not shown), like the selector switch shaft, carries the line wipers 108 and 109 and the private wiper 110. The connector switch is also controlled by the calling subscriber through the medium of the vertical and rotary line relays 111 and 112. The vertical line relay 111 directly controls the vertical magnet 113, the rotary magnet 114, the rotary magnet 99 of the ringer selector, and the ringer relay 115. The purpose of the vertical magnet 113 is to give the shaft and shaft wipers their vertical motion, and the rotary magnet 114 imparts to the shaft wipers a rotary or circular motion. As before explained, the rotary magnet 99 operates the ratchet wheel 103, and the ringer relay 115, upon energizing, operates to bridge the terminals of one of the ringer generators across the terminals of the called line. The rotary line relay 112 controls the private magnet 116, which latter, under certain conditions, controls in turn the vertical magnet 113 and the two rotary magnets 114 and 99, the ringer relay 115, the release magnet 117, and the side switch which comprises the wipers 118, 119, 120 and 121. The side switch of the connector, unlike the side switch of the selectors C and D, has four positions, a normal or first position, a second position, a third position and a fourth position. The release magnet 117 is also controlled by the vertical and rotary line relays 111 and 112 conjointly. By the use of the condensers 122 and 123 the circuit through the connector is divided into two sections. The

busy signaling apparatus H may be of any suitable design as, for example, the one comprising the interrupter 124 in series with the primary winding 125 of the induction-coil 126, whereby a busy signal is in turn induced in the secondary winding 127. The secondary winding is connected with the second-position contact point 125^a.

The operation of my improved party-line arrangement may be more clearly understood from a description of its operation, as follows: To call the subscriber at substation A³, whose number it is assumed is 24213, the subscriber at substation A, whom it is assumed is doing the calling, removes his receiver from the switch-hook and operates his calling device once in the well-known manner for each digit. When the dial returns to normal position for the first digit the first-selector switch C is operated to establish connection with the second-selector switch D. The impulses for the second digit operate the second-selector switch D, while the impulses for the last three digits are directed toward the connector switch E, which operates to place its wipers in connection with the contacts corresponding to the desired line, and also to select the ringer generator R which is adapted to signal the substation A³. Still more in detail, the calling operations are as follows: When the subscriber removes the receiver from the switch-hook 3, and operates the dial for the first digit 2, the vertical line conductor 31 is grounded twice and the rotary line conductor 32 is grounded once when the impulse springs 24 and 23 are pressed onto the ground post 20. As a result, the vertical line relay 65 of the first-selector C is energized each time by a flow of current from the substation ground G¹ through the springs 40 and 41, ground springs 18 and 19 to the ground post 20, impulse spring 23, vertical line conductor 31, side switch wiper 48, contact point 53, vertical line relay 65, bridge-cut-off springs 128 and 129 to the battery lead 130, thence through battery B to ground G. Each time that the vertical line relay 65 energizes, the line relay springs 131 and 132 are pressed into contact, thereby closing an energizing circuit through the vertical magnet 66 extending from ground G² through the springs 131 and 132, private magnet springs 133 and 134, through the vertical magnet 66 to the battery lead 130, thence through battery B to ground G. The vertical magnet is thereby energized, and the wipers 45, 46 and 47 of the selector C are raised to the second bank level and brought opposite the first contact. Following the vertical impulses the rotary impulse spring 24 is pressed onto the ground post 20, grounding the rotary line conductor 32 and energizing the rotary line relay 67 of the selector C. The ener-

gizing circuit passes from ground G¹ to the ground post 20, through the impulse spring 24 to the line conductor 32, normal springs 74 and 73, side switch wiper 49, contact point 54, rotary line relay 67, bridge-cut-off relay springs 135, 128 and 129 to the battery lead 130, thence through battery B to ground G. As previously explained, when the selector shaft is given the first vertical step the normal arm 72 permits the normal spring 73 to engage the spring 74, thereby connecting the rotary line conductor 32 with the side switch wiper 49. The rotary line relay upon energizing presses the line relay spring 136 onto the ground spring 131, thereby establishing an energizing circuit through the private magnet 52 from ground G², through the springs 131 and 136, private magnet 52 to the battery lead 130, thence through battery B to ground G. The private magnet, upon energizing and de-energizing, permits the selector side switch to pass from first to second position, whereby the side switch wipers 50 and 51 engage the contact points 59 and 60, respectively. The closure of contact between the contact point 51 and the contact point 60 sets up an energizing circuit through the rotary magnet 68 from ground G³ to the contact point 60, side switch wiper 51, interrupter spring 137, through the rotary magnet 68 to the battery lead 130, thence through battery B to ground G. Said rotary magnet 68 then operates to rotate the wipers 45, 46 and 47 into engagement with the first contact of the second level of the selector banks, from which contact it is assumed that the trunk conductors 138, 139 and 140 lead to the selector switch D. However, if the first trunk-line is busy and the wipers have to pass over busy trunk-lines, then as soon as the private wiper 47 engages the first busy private bank contact the private magnet 52 again energizes, locking the side switch in second position. The energizing circuit for the said private magnet extends from the grounded terminal of battery B through an occupying switch (not shown), through the private wiper 47, then through the back-release relay 69, side switch wiper 50, contact point 59, through the private magnet 52 to the battery lead 130, thence through battery B to ground G. Upon thus becoming energized the private magnet 52 locks the side switch wiper 51 in engagement with the contact point 60, whereby the rotary magnet 68 will be energized step by step until the wipers are carried beyond the last busy contact. Then, the instant that the private wiper 47 leaves the last busy contact point the energizing circuit through the private magnet 52 is destroyed, and as a result the selector side switch passes to third position. If there are no busy trunk-lines, as assumed, the pri-

vate magnet 52 releases the side switch to third position as soon as the wipers are carried into engagement with the first trunk-line. As soon as the side switch passes to 5 third position, as stated, the main line conductors 31 and 32 are extended to the conductors 138 and 139 which, in this case, lead to the second-selector switch D. Not only is the subscriber's line extended, but a guarding potential is established at the private wiper 47 for protecting the seized trunk-line from interference by other calling subscribers. This guarding potential extends from ground G^1 through the side switch 10 wiper 50, back-release relay 69 to the private wiper 47. It will be seen, of course, that the energizing circuit for the rotary magnet 68 is destroyed when the idle trunk-line is seized—that is, when the side switch wiper 51 leaves the contact point 60. Also, when the side switch wiper 50 engages the contact point 63 a guarding potential is established at the connector bank to prevent a calling subscriber from establishing connection with 15 the normal conductors 75, 76 and 77 while the selector C is busy. This potential extends from ground G^1 through the side switch wiper 50 to the conductor 144, through the springs 145 and 146, private 20 conductor 77, which leads to the connector bank contact corresponding to the line conductors 31 and 32. The grounding of the main line conductors 31 and 32 for the second digit 4 is effective in operating 25 the selector switch D to establish connection with the trunk conductors 147, 148 and 149 which lead to the connector E. Grounding the vertical line conductor 31 energizes the vertical line relay 91, which in turn operates 30 to close an energizing circuit through the vertical magnet 78. The vertical magnet 78 operates in the usual manner to carry the shaft wipers 87, 88 and 89 upwards four steps. Grounding the rotary line conductor 35 32 closes the energizing circuit through the rotary line relay 92, which in turn operates to close an energizing circuit through the private magnet 81. The private magnet operates as usual to pass the side switch to 40 second position, whereby an energizing circuit is closed through the rotary magnet 79, which operates to place the shaft wipers 87, 88 and 89 in engagement with the first idle trunk-line. When the side switch wipers 81^a 45 and 82 pass to third position the line conductors 31 and 32 are extended to the connector trunk-line conductors 147 and 148, respectively. The grounding of the main line conductors 31 and 32 for the next two digits 50 2 and 1 affects the connector by operating the vertical and rotary line relays 111 and 112. When the vertical line conductor 31 is grounded the vertical line relay 111 is energized by a flow of current from the sub- 55 station ground G^1 , vertical impulse spring 60 23, conductors 31, 138 and 147, through the winding of the vertical line relay 111 to the battery lead 130, thence through battery B to ground G . Each time that the vertical line relay operates, the vertical magnet 113 65 70 operatively energizes to carry the shaft wipers 108, 109 and 110 in a vertical direction, one step at a time, until the said wipers are carried two steps and thus brought to a level in which are located the terminals of the line #24213. The circuit through the vertical magnet extends from ground G^5 through the springs 150 and 151, through the private 75 springs 152 and 153, side switch wiper 121, 80 vertical magnet 113 to the battery lead 130, thence through battery B to ground G . When the rotary line conductor 32 is grounded, following the grounding of the vertical line conductor 31, the connector rotary line relay 112 becomes energized over a circuit extending from ground G^1 to the impulse spring 24, conductors 32, 139 and 148, through the winding of the rotary line relay 112, springs 154 and 155 to the battery 85 lead 130, thence through battery B to ground G . The rotary line relay upon energizing operates to close an energizing circuit through the private magnet 116, which latter in turn operates to release the side switch 90 from first to second position. The energizing circuit through the private magnet 116 extends from ground G^5 through the springs 150 and 156, through the private magnet 116 to the battery lead 130, thence through 95 battery B to ground G . For the next digit the subscriber operates the dial as previously explained, grounding the vertical line conductor once and the rotary line conductor 100 32 once. The connector vertical and 105 rotary line relays 111 and 112 are operated over previously traced circuits. However, when the vertical line relay 111 operates, a circuit is closed through the rotary magnet 114 instead of through the vertical magnet 113, since the side switch wiper 121 has passed from first to second position. When the rotary magnet 114 is energized the shaft wipers 108, 109 and 110 are rotated one step 110 and the said wipers are carried into engagement with the normal conductors 157, 158 and 159, the first two of which lead to the main line terminals of the desired substation. The rotary line relay 112, upon energizing, completes an energizing circuit 115 through the private magnet 116, as before, which latter now operates with one of two results, namely the release of the side switch from second to third position, or the so-called busy-release of the connector. It will 120 be assumed that the former result occurs, and that the side switch passes to third position, whereby the side switch wipers 120 and 121 are placed in connection with the 125 contact points 160 and 161, respectively, and 130

the wiper 120 is placed in connection with the contact 160, thus establishing a guarding potential for protecting the called line. This potential extends from ground G^c to the side 5 switch wiper 120 and the private shaft wiper 110, which engages the private contact of the called line. For the last digit 3 the dial is again operated, grounding the vertical line conductor 31, which operates 10 the vertical line relay 111, as explained. The vertical line relay, upon energizing, operates to close an energizing circuit through the rotary magnet 99 extending from the ground G^c through the springs 150 and 151, 15 private magnet springs 152 and 153, side switch wiper 121, contact point 161, through the winding of the rotary magnet 99 to the battery lead 130, thence through battery B to ground G. The vertical line relay being 20 energized three times, the rotary magnet 99 is in turn also energized three times, whereby by the ratchet wheel 103 is given three steps, and the wipers 105 and 106 are placed in contact with the bank terminals 162 and 163 25 to which is connected the ringer generator R^s . The rotary line relay, upon energizing for the last digit, again operates to close an energizing circuit through the private magnet, which latter, upon energizing and de- 30 energizing, permits the side switch to pass to fourth position. Of course, when the side switch passes to third position the guarding potential for the called line is still maintained, as shown. Also, when the shaft 35 wiper 110 engages the private contact, and the side switch wiper 120 passes to third position, an energizing circuit is then established through the bridge-cut-off relay 164 of the selector F (Fig. 2). This circuit extends 40 from ground G^c through the side switch wiper 120, private shaft wiper 110, private trunk conductor 159, through the spring 165, side switch wiper 166, conductor 167, through the bridge-cut-off relay 164 to the 45 battery lead 130, thence through battery B to ground G. The calling subscriber having operated the calling device in accordance with the digits of the desired number 24213 is now ready to signal the subscriber at sub- 50 station A^s , which is done by pressing the button 37, whereby the spring 35 is carried onto the ground contact point 38, thereby grounding the vertical line conductor 31 and completing an energizing circuit through the 55 vertical line relay 111. It will be remembered that the connector side switch has passed from third to fourth position, and that the side switch wiper 121 now engages the contact point 168, thereby placing the vertical 60 line relay 111 in control of the ringer relay 115 in the same manner in which the rotary magnet 114 came under the control of the vertical line relay when the side switch passed from first to second position. There- 65 fore, when the vertical line relay 111 presses

the springs 150 and 151 into contact, the ringer relay 115 is energized by a flow of current from ground G^c through the springs 150 and 151, private magnet springs 152 and 153, side switch wiper 121, contact point 168, 70 through the ringer relay 115 to the battery lead 130, thence through battery B to ground G. The ringer relay, upon energizing, operates to shift the springs 169 and 170 from the springs 171 and 172 to the springs 173 75 and 174, and the springs 154 and 155 are also disengaged. The shifting of the springs 169 and 170 results in bridging the terminals of the ringer generator R^s across the called line. The signaling current is, therefore, sent from the generator R^s to the bank contact 162, wiper 105, through the ringer relay springs 174 and 170, side switch wiper 118, shaft wiper 108, normal conductor 157, main line conductor 175, through the switch- 80 hook 176, spring 177, through the ringer 178, condenser 179 to the rotary line conductor 180, normal conductor 158, shaft wiper 109, side switch wiper 119, ringer relay springs 169 and 173, wiper 106, bank contact 163 and 90 back to the ringer generator R^s . The signaling current also passes through the ringers 181 and 182 of the substations A^s and A^s in multiple with the ringer 178 of substation A^s ; but, as previously explained, only the 95 ringer 178 is arranged to respond to signaling current from the ringer generator R^s , and hence only the ringer at substation A^s is sounded. As soon as the calling subscriber ceases to press the signaling button 35, the 100 ringer relay 115 becomes de-energized, and the springs 169 and 170 return to their normal positions. The subscriber at substation A^s , in response to the signal, removes the receiver 183 from the switch-hook 184, 105 whereby the switch-hook rises and permits the springs 185 and 186, and also the springs 187, 188 and 189, to engage. The engagement of the springs 185 and 186 closes a secondary circuit which includes 110 the receiver 183 and the secondary winding 190. The engagement of the springs 187, 188 and 189 closes the primary circuit which includes the transmitter 191, local battery 192 and the primary winding 193. The two 115 subscribers are now connected and conversation may be carried on over the circuits shown by the heavy line conductors in Figs. 1 and 2. Suppose that while the two substations are thus connected the subscriber at substation A^s (Fig. 1) removes his receiver from the switch-hook, preparatory to making a call. In that event, an energizing circuit is established through the ground cut-off relay 194 extending from 120 ground G^s through the springs 195 and 196 and the springs 197 and 198, through the cut-off relay 194, springs 199 and 200 to the rotary line conductor 32, trunk conductors 139 and 148, through the rotary line relay 125 130

112 to the battery lead 130, thence through battery B to ground G. The relay 194 thereupon energizes, attracting its armature 201 which operates to separate the springs 5 195 and 196, thereby opening the circuit through the relay 194 and disconnecting the substation ground G^7 from the ground spring 202, whereby the substation is deprived of ground connection for operating 10 the central office switches. The substation is thus rendered powerless to interfere with the established connection. Also, when the relay 194 energizes, the spring 203 rises in front of the armature 201, locking the latter in its attracted position. When the receiver is restored to the switch-hook the arm 204 carries the locking spring 203 out of engagement with the armature 201, and the springs 195 and 196 again engage. 15 Also, a subscriber at substation A^4 on the called line is prevented from interfering with an established connection, since the bridge-cut-off relay 164 of the first-selector F is energized, and the vertical and rotary line relays 205 and 206 are disconnected from the battery lead 130. The release of the central office switching apparatus is brought about when the calling subscriber restores the receiver 2 to the switch-hook 3, 20 thereby pressing the release springs 7, 8 and 9 into engagement for a moment. The contact of the said springs grounds the vertical and rotary line conductors 31 and 32 simultaneously from ground G^4 to the release spring 7, thence through the springs 8 and 9 to the vertical and rotary line relays 35 111 and 112. Said relays, upon energizing simultaneously, press the springs 207 and 208 into contact, whereby an energizing circuit is established through the release magnet 117 of the connector E in series with the back-release relay 98 of the second-selector D. This circuit extends from ground G^8 through the side switch wiper 83, back-release 40 relay 98, shaft wiper 89, conductor 149, trunk-release springs 207 and 208, through the release magnet 117 to the battery lead 130, thence through battery B to ground G. When the connector release magnet is thus 45 supplied with current it energizes, and as a result the switch shaft and side switch are restored to normal position, thus breaking the connection between the connector switch shaft wipers 108, 109 and 110 and the normal conductors 157, 158 and 159. The engagement of the trunk-release springs 207 and 208 also closes an energizing circuit through the release magnet 100. This circuit extends from ground G^8 through the 50 back-release relay 98, trunk-release springs 207 and 208, through the winding of the release magnet 100 to the battery lead 130, thence through battery B to ground G. This magnet, upon energizing, draws the 55 ratchet pawl armature 104 out of engage- ment with the ratchet tooth of the wheel 103. The ratchet wheel 103 now returns to normal position, with the wipers 105 and 106 to the left of the contacts 107. The back-release relay 98, being in the same circuit with the release magnet, energizes simultaneously with the latter, and operates to close an energizing circuit through the release magnet 80 of the selector D in series with the back-release relay 69 of the selector 70 C. This circuit extends from ground G^4 through the side switch wiper 50, back-release relay 69, private shaft wiper 47, conductor 140, through the springs 209 and 210, through the release magnet 80 to the battery lead 130, thence through battery B to ground G. When the back-release relay 69 energizes and places the springs 211 and 212 in contact an energizing circuit is established through the release magnet 68^a of the first-selector C. This circuit from ground G^9 through the springs 211 and 212, release magnet 68^a to the battery lead 130, thence through battery B to ground G. When the ground connection to the line conductors 85 31 and 32 is interrupted all the magnets involved in the release are de-energized and all the switches fully restored. 90

If the line to which the substation A_3 is allotted is busy at the time the calling subscriber at substation A attempts to establish a connection, the connector E is released by the rotary impulse for the next to the last digit. Said impulse energizes the rotary line relay 112, which relay in turn energizes the private magnet 116, pressing the private springs 213 and 214 into engagement after the private wiper 110 has been carried onto the grounded private bank contact. It is understood, of course, that whenever a 95 line is busy the connector private bank contacts connected with the private normal conductor are all connected to ground. Therefore, since the connector side switch is in second position when the private magnet 100 springs 213 and 214 are brought into contact, an energizing circuit is established through the release magnet 117 from the said grounded private bank contact to the private wiper 110, through the side switch wiper 120, which 105 is in second position, to the contact point 260, through the private magnet springs 214 and 213, through the release magnet 117 to the battery lead 130, thence through battery B to ground G. When the release magnet 115 is energized the connector switch shaft and side switch are released and connection is not established through the called line, and the connector mechanism returns to normal position. Now, when the subscriber operates the dial for the last digit 3 the connector vertical and rotary line relays are energized, and the vertical magnet is given three steps 110 and the private magnet is energized once. The energization and de-energization of the 115 120 125 130

private magnet permits the side switch to pass from first to second position. The calling subscriber, having thus operated the dial for the digits of the number 24213, thinks 5 that the desired connection is established and operates the signaling button 37, which grounds the vertical line conductor 31, thus completing an energizing circuit through the vertical relay, which in turn operates to 10 close an energizing circuit through the rotary magnet 114 instead of through the ringer relay 115. The calling subscriber, waiting to receive a response from the called subscriber, receives the busy-signal instead, 15 as follows: From the battery lead 130, through the secondary winding 127 of the induction-coil 126, contact point 125^a (remembering that the side switch is now in second position) to the side switch wiper 119, 20 ringer relay springs 169 and 171, through the condenser 123, trunk conductors 148 and 139, rotary line conductor 32, condenser 12, through the receiver 2, secondary winding 22, through the springs 33 and 34 to the 25 vertical line conductor 31, thence through the trunk conductors 138 and 147, through the winding of the vertical line relay 111 to the battery lead 130. Of course, when the calling subscriber hangs up his receiver after 30 receiving the busy-signal, he grounds the vertical and rotary line conductors 31 and 32, thereby energizing the vertical and rotary line relays 111 and 112 of the connector E, as already explained, producing a release 35 of the switching apparatus as formerly.

From the foregoing it will be seen that I provide a step-by-step and automatic switch for enabling the calling subscriber, or any other person, to select the desired generator 40 or source of ringing current and connect the same with the called line. Also, it will be seen that this switch for selecting and connecting the generators or sources of ringing current with the called lines is subject to 45 substation control. With this arrangement a subscriber, in calling a party-line subscriber, operates his dial for all of the digits of the called number except the last, and thereby operates the trunking means for 50 finding the called line. When the dial or calling mechanism of the calling subscriber is then operated for the last digit of the called number, this results in the selection by the calling subscriber of the desired generator, and in the connection of 55 the same with the party-line. Then when the calling subscriber presses his ringing button, the proper or desired frequency of current flows out upon the party-line, 60 and only the ringer at the substation of the called subscriber responds. In other words, when the subscriber rotates his dial for the last digit of the called number, the so-called vertical impulses cause the vertical line relay of the connector to operate 65

the step-by-step generator switch to the required position, and the final rotary impulse trips the side switch of the connector to fourth position. Thus, by practically one operation of the calling dial the calling subscriber closes or makes the final connection in the trunk circuit between the two lines, and at the same time selects the proper generator for use in ringing the bell at the station of the called subscriber. Of course, 75 the connection of the generator to the contacts of the ringer relay occurs just ahead of the movement of the side switch to fourth position. Also, the flow of ringing current in the called line does not occur until the 80 calling subscriber presses his button or ringing key.

What I claim as my invention is:—

1. In a telephone system, a party-line equipped for selective signaling, means by 85 which a calling subscriber calls any party-line subscriber by transmitting electrical impulses, means responsive to all except the last impulses for finding the party-line, means responsive to the impulses for the 90 last digit for selecting the means by which to signal only the called subscriber on said line, and a trunk-release circuit for restoring the central office signaling means to normal condition. 95

2. In a telephone system, a party-line equipped for selective signaling, automatic means for finding the line in accordance with all except the last digit of the number 100 of any subscriber thereon, means for signaling across the line in accordance with the last digit of such number, and a trunk-release circuit for restoring the central office signaling means to normal condition. 105

3. In a telephone system, a party-line equipped for selective signaling, automatic means for trunking a calling subscriber to the said line in accordance with all except the last digit of the number of any subscriber thereon, means for signaling across 110 the line in accordance with the last digit of such number, and a trunk-release circuit for restoring the central office signaling means to normal condition. 115

4. In a telephone system, a party-line equipped for selective signaling, subscriber-controlled automatic means for finding said line in accordance with all except the last digit of the number of any subscriber thereon, suitable means for signaling across the 120 line in accordance with the last digit of such number, and a trunk-release circuit for restoring the central office signaling means to normal condition. 125

5. In a telephone system, a party-line equipped for selective signaling, suitable means for connecting with the said line in accordance with all except the last digit of the number of any subscriber thereon, subscriber-controlled means for signaling across 130

- the line in accordance with the last digit of such number, and a trunk-release circuit for restoring the central office signaling means to normal condition.
5. 6. In a telephone system, a connector including relays and provided with a side switch having only four positions, means for controlling said connector in accordance with the first two of the last three digits of 10 the number of a called subscriber, and another switch controlled by a relay of the connector in accordance with the last digit after the called line is found.
7. In a telephone system, an automatic connector provided with a side switch having only four positions, a party-line adapted to be seized by said connector, and means for controlling said connector in accordance with only the first two of the last three digits of 15 20 the number of any subscriber on said line.
8. In a telephone system, an automatic connector provided with a side switch having four positions, means for moving said side switch from one position to another to enable the connector to find the called line, and means for signaling the called subscriber after the side switch moves to fourth 25 position.
9. In a telephone system, an automatic connector provided with a side switch having four positions, means for moving the side switch from one position to another to enable the connector to find the called line, a plurality of sources of ringing current, 30 35 means operative when the side switch is in third position for selecting any source of current, and means for projecting said ringing current onto a called line after the side switch has moved to fourth position.
- 40 10. The combination, in an automatic telephone exchange, of a party line equipped for selective signaling, means to signal the called subscriber, a calling subscriber's mechanism and means responsive thereto for finding the said party line, means responsive to said mechanism for selecting the means to signal only the called subscriber on said line, operative only after the called line is found, and a trunk-release circuit including a third 45 50 conductor for restoring the central office signaling means to normal condition.
11. The combination, in an automatic telephone exchange, of a party line equipped for selective signaling, means by which a calling subscriber calls any party line subscriber by transmitting electrical impulses, means responsive to all except the last impulses for finding the party line, means responsive to the impulses for the last digit 55 60 65 for selecting the means by which to signal only the called subscriber on said line, operative only after the called line is found, and a trunk-release circuit including a third conductor for restoring the central office signaling means to normal condition.
12. The combination, in an automatic telephone exchange, of a party line equipped for selective signaling, a calling mechanism, means responsive to said mechanism for finding the party line, as many different 70 sources of ringing current as there are subscribers on said line, means responsive to said mechanism for selecting the source of current by which to signal only the called subscriber on said line, operative only after 75 the called line is found, and a trunk-release circuit including a third conductor for restoring the central office signaling means to normal condition.
13. The combination, in an automatic 80 telephone exchange, of a party line equipped for selective signaling, automatic means for finding the line in accordance with all except the last digit of the number of any subscriber thereon, means for signaling in 85 accordance with the last digit of such number, operative only after the called line is found, and a trunk-release circuit including a third conductor for restoring the central office signaling means to normal condition. 90
14. The combination, in an automatic telephone exchange, of a party line equipped for selective signaling, automatic means for trunking a calling subscriber to the said line in accordance with all except the last digit 95 of the number of any subscriber thereon, means for signaling in accordance with the last digit of such number, operative only after the called line is found, and a trunk-release circuit including a third conductor 100 for restoring the central office signaling means to normal condition.
15. The combination, in an automatic telephone exchange, of a party line equipped for selective signaling, subscriber-controlled 105 automatic means for finding said line in accordance with all except the last digit of the number of any subscriber thereon, suitable means for signaling in accordance with the last digit of such number, operative only 110 after the called line is found, and a trunk-release circuit including a third conductor for restoring the central office signaling means to normal condition.
16. The combination, in an automatic 115 telephone exchange, of a party line equipped for selective signaling, suitable means for connecting with the said line in accordance with all except the last digit of the number of any subscriber thereon, subscriber-controlled means for signaling in accordance with the last digit of such number, operative only after the called line is found, and a trunk-release circuit including a third conductor 120 for restoring the central office signaling means to normal condition.
17. The combination, in an automatic telephone exchange, of a connector provided with a side switch having four positions, and means for controlling said connector in ac- 125 130

cordance with only the first two of the last three digits of the number of the called subscriber to find the called line.

18. The combination, in an automatic telephone exchange, of an automatic connector provided with a side switch having four positions, a party line adapted to be seized by said connector, and means for controlling said connector in accordance with 5 only the first two of the last three digits of the number of any subscriber on said line to find the called line.

19. The combination, in an automatic telephone exchange, of an automatic connector provided with a side switch having four positions, means for moving said side switch from one position to another to enable the connector to find the called line, and means for signaling the called subscriber 15 while the side switch is in fourth position, operative only after the called line is found.

20. In a telephone system, a calling subscriber's line, a party line, a final connector switch, a line relay individual to said connector, a circuit for said relay including a conductor of the calling line, operating magnets in said connector controlled by said relay responsive to trains of impulses transmitted over said circuit for setting the wipers 25 of said connector on party line, different sources of ringing current equal in number to the stations on said party line, an auxiliary ringing current selecting switch, a magnet for shifting the control of said relay 30 from the connector operating magnets to the operating magnets of said auxiliary switch in order to select one of said sources responsive to another train of impulses, and means for connecting the selected source to the said 35 party line to signal the desired station.

21. In a telephone system, a calling subscriber's line, a party line, a final connector switch, a line relay individual to said connector, a circuit for said relay including a conductor of the calling line, operating magnets in said connector controlled by said relay responsive to trains of impulses transmitted over said circuit for setting the wipers 45 of said connector on said party line, different sources of ringing current equal in number to the stations on said party line, an auxiliary ringing current selecting switch, a magnet for shifting the control of said relay from the connector operating magnets to 50 the operating magnet of said auxiliary switch in order to select one of said sources responsive to another train of impulses, and a ringing relay controlled by said line relay thereafter to bridge the selected source across 55 the wipers of said connector to signal the desired station on said party line.

22. In a telephone system, a trunk line terminating in a connector switch, a party line accessible to said connector, operating 65 magnets in said connector, a line relay in

said connector responsive to trains of impulses transmitted over a conductor of said trunk line for actuating said magnets to cause the connector to connect with said party line, different sources of ringing current equal in number to the stations on said party line, a ringing current selecting switch, an operating magnet in said selecting switch controlled by said line relay responsive to a subsequent series of impulses for causing 70 said selecting switch to select one of said sources, a magnet for shifting the control of said line relay from the last connector operating magnet to the operating magnet of said selecting switch at the proper time, and means for connecting the selected source to the said party line via the wipers of said connector to signal the corresponding station. 75

23. In a telephone system, a trunk line terminating in a connector switch, a party line accessible to said connector, operating magnets in said connector, a line relay in said connector responsive to trains of impulses transmitted over a conductor of said trunk line for actuating said magnets to cause the connector to connect with said party line, different sources of ringing current equal in number to the stations on said party line, a ringing current selecting switch, an operating magnet in said selecting switch controlled by said line relay responsive to a subsequent series of impulses for causing 80 said selecting switch to select one of said sources, a magnet for shifting the control of said line relay from the last connector operating magnet to the operating magnet of said selecting switch at the proper time, and a ringing relay controlled by said line relay for connecting the selected source to said party line via the wipers of said connector to signal the corresponding station. 85

24. In a telephone system, a trunk line terminating in a connector switch, a party line accessible to said connector, a line relay in said connector responsive to successive trains of impulses transmitted over said trunk line, different sources of ringing current, a ringing current selecting switch, operating magnets for said connector and said selecting switch controlled successively by said line relay to set said connector on said party line and select a particular one of said sources, a magnet for shifting the control of said line relay from the last connector operating magnet to the selecting switch operating magnet 90 at the proper time, and means for connecting the selected source to said party line to signal a particular one of said stations. 95

25. In a telephone system, a trunk line terminating in a connector switch, a party line accessible to said connector, a line relay in said connector responsive to successive trains of impulses transmitted over said trunk line, sources of ringing current of different character, a ringing current select- 100 105 110 115 120 125 130

ing switch having two wipers, operating magnets for said connector and selecting switch controlled successively by said line relay to set said connector on said party line 5 and to select a particular one of said sources, a signalling circuit including the two wipers of said selecting switch and the line wipers of said connector for bridging the selected source across said party line, and means for

closing said circuit in the connector to signal 10 a particular station on said party line.

Signed by me at Chicago, Cook County, Illinois, this 26th day of November, 1907.
